UNITED STATES PATENT OFFICE.

GEORGE RAWLINS, OF GOLDEN HILL, ENGLAND.

FAUCET OR TAP.

SPECIFICATION forming part of Letters Patent No. 629,304, dated July 18, 1899.

Application filed December 19, 1898. Serial No. 699,637. (No model.)

To all whom it may concern:

Be it known that I, GEORGE RAWLINS, a citizen of the Kingdom of Great Britain and Ireland, residing at Acres Nook, Golden Hill, 5 Stafford county, England, have invented a new and useful Improvement in Faucets or Taps, of which the following is a specification.

My invention relates to faucets or taps for barrels, casks, and similar receptacles; and its novelty consists in the construction and adaptation of the parts, as will be more fully hereinafter pointed out. It is designed more particularly to overcome the common difficulties met with from leakage and spilling when new taps or faucets are attempted to be inserted in such fluid-receptacles.

In the drawings, Figure 1 is a central vertical section of the two bushings into which the tap is to be inserted and the valve which closes the aperture into which they are inserted, a portion of the cask being shown also. Fig. 2 is a rear elevation of the bushing *a*. Fig. 3 is a central vertical section of the two bushings, the coupling, and part of the tap-stem and a side elevation of the rest of the tap-stem and the faucet. Fig. 4 is a side elevation of a part of the tap-stem.

In the drawings, *a* is a cylindrical bushing 30 laterally provided with a plurality of apertures or perforations *d* and provided at its rear vertical face with a hole *a'* of suitable size to admit of the passage of the stem *e* of the conical valve *g* and for which valve-stem it forms a guide and bearing. At its forward end the bushing *a* is internally threaded at *a*² and adapted to engage with a similarly externally-threaded portion *b'* of a second bushing *b*. This bushing *b* is likewise cylindrical in general shape. It is internally threaded at its forward end at *b*² and is provided with an outwardly-extending flange *b*³, provided with suitable apertures to admit of the passage of screws *b*⁴ or the like, by which it may be secured to the cask *c*. By unscrewing bushing *a* the valve and its spring may be removed for examination when the end of the cask or barrel is taken out. This should be done after each third emptying.

50 The tap or faucet *l*, furnished with the usual cock or valve *l'*, is provided at the rear with a tap-stem *i*. This tap-stem is provided with

an annular collar *i'*, secured thereto or made integral therewith, and at the rear of which is placed an annular washer *i*², made of leather or other suitable material. At its extreme rear portion the tap-stem is provided with a plurality of suitable apertures or perforations *k*, affording access to its interior, and its extreme inner periphery is chamfered 60 at *k'* by suitable indentations and beveled off, as at *k*², to form a seat for the conical valve *g*.

A supplementary cylindrical bushing or coupling-piece *j*, externally threaded at *j*² and 65 adapted to engage with the internal threads of the bushing *b*, is made of sufficient size to fit easily over the tap-stem *i*. Its rear end is adapted to bear against the annular collar *i'* on the tap-stem, and it is provided with outwardly-projecting wings or thumb-pieces *j*² 70 for facilitating its rotation by hand.

Intermediate the inner wall of the bushing *a* and the rear of the tap-stem *i* is placed the conical valve *g*, made of metal or other suitable material and adapted to rest against the seat *k*², formed by the inner end of the said tap-stem and the rear inner edge of the bushing *b*. The valve is provided with a rearwardly-projecting stem *e* and is normally held against 80 its seat by the retraction of a spring *f*, coiled around the valve-stem and bearing against the rear wall of the bushing *a*.

It is obvious that, when the two bushings *a* and *b* are in place, and the valve *g* is within 85 the chamber of the bushing *a*, although liquid within the cask may flow through the apertures *d* and completely fill such chamber, yet it is prevented from going farther by reason of the valve *g*, which, seated against the rear 90 inner edge of the bushing *b*, effectually closes it. When, however, it is desired to attach the tap or faucet to the cask, the tap-stem *i* is introduced within the bushing *b* and the supplementary bushing or coupling-piece *j* 95 screwed therein, and as the thumb-pieces *j*² are turned the rear end of the coupling presses against the collar *i'* on the tap-stem and forces the latter rearward. As this action continues it moves the valve *g* also rearward and through 100 the apertures *k* and the indentations *k'* of the tap-stem permits access between the latter and the chamber within the bushing *a* and through the apertures *d* with the interior of the cask.

I prefer that the flange b^3 of the bushing b should be made flush with the outer surface of the cask; but of course such construction is not material. The advantages of my device are quite obvious. A cask provided with my improved bushing is securely closed, and yet the faucet may be promptly attached to it by the most inexperienced person without risk of waste or leakage. During transportation the aperture across the mouth of the bushing b may be closed by a seal or in any suitable manner. The valve g is simple and inexpensive and may be readily removed for cleansing and replaced when worn. It is only necessary to remove the bushing a to gain access to the valve and its spring.

What I claim as new is—
The combination with a cask, or the like, having a bushing provided at its outer end

with an internally-threaded opening and externally threaded on its inner end, a second bushing engaging said external thread and having a series of perforations therein; a valve having its rod guided by such second bushing, a spring for the valve, said valve, its rod and spring being located wholly in the second bushing, a faucet or tap having a perforated stem designed to engage said valve, a collar on said stem, and a threaded coupling screwed into said internally-threaded opening and designed to engage said collar on said stem, substantially as set forth.

In witness whereof I have hereunto set my hand in the presence of two witnesses.

GEORGE RAWLINS.
